UNITED STATES PATENT OFFICE.

CLARA J. CLARKE, OF FREMONT, OHIO.

DESIGN FOR A DRESSER.

SPECIFICATION forming part of Design No. 35,978, dated July 15, 1902.

Application filed April 23, 1902. Serial No. 104,403. Term of patent 14 years.

To all whom it may concern:

Be it known that I, CLARA J. CLARKE, a citizen of the United States, residing at and whose post-office address is Fremont, in the county of Sandusky and State of Ohio, have invented a new and original and ornamental Design for a Dresser, of which the following is a specification.

This invention relates to a new and original design for a dresser, and the essential features reside in the design as illustrated in the accompanying drawing, wherein is shown a perspective view of the dresser designed in accordance with the invention.

The numerals 1, 2, and 3 designate members of the dresser, which are of upright form and approximately rectangular in contour, the two members 2 and 3 continuing from opposite sides of the central member 1 in outward angles. The front of the member 1 has a glass panel extending almost the full length thereof and an ornamental cap 5. The front faces of the members 2 and 3 are also provided with upper panels 6 and 7, respectively, and top caps 8 and 9, continuing from the central cap 5 of the member 1, ornamental caps 10 also projecting from the top portions of the members 2 and 3 in planes at right angles to the caps 8 and 9 and close to the plane of the exposed ends 11 of the said members 2 and 3. Below the panels 6 and 7 each of the members has a plurality of transversely-extending projecting ribs 12, and near the top of the panels 6 and 7 is a similarly-disposed rib 13. The ends 11 of the members 2 and 3 also have panels 14, one in each, extending almost the full vertical length of the same. All the members have upper and lower closed ends.

Having thus fully described the invention, what is claimed as new is—

The ornamental design for a dresser, as herein shown and described.

In testimony whereof I affix my signature in presence of two witnesses.

CLARA J. CLARKE.
